DEVICE FOR CUTTING TREAD RUBBER FROM VEHICLE TIRES

James W. Heaton, Greensburg, and William E. Fawcett,
Latrobe, Pa., assignors to Kennametal Inc., Latrobe, Pa.

Filed June 26, 1974, Ser. No. 483,102

Term of patent 14 years

Int. Cl. D15—99

U.S. CL. D15—127

FIG. 1

FIG. 3

FIG. 2

FIG. 4

FIG. 1 is a side elevational view of a new device for cutting tread rubber from vehicle tires looking in at the cutter from one side.

FIG. 2 is a view like FIG. 1 but looking in at the device from the other side.

FIG. 3 is a view of the cutter looking in from the right side of FIG. 1 with the central part of the device broken away to show the central bore in the cutter.

FIG. 4 is a fragmentary sectional view indicated by line 4-4 to show the cross sectional configuration of the body of the device.

We claim:

The ornamental design for a device for cutting tread rubber from vehicle tires, substantially as shown.
